BUFFING WHEEL

John F. Leslie, Mishawaka, Ind.

Application September 1, 1948, Serial No. 47,207

9 Claims. (Cl. 51—193)

1

This invention relates to improvements in buffing wheels, and more particularly to a buffing wheel of the type wherein a rigid center part has detachably secured at its periphery a plurality of fabric members which cooperate therewith to provide a peripheral buffing portion.

Previous constructions of buffing wheels of this character have been subject to certain disadvantages, and particularly have been difficult to assemble and disassemble. These difficulties have occasioned the requirement for the expenditure of large amounts of time in assembling and disassembling a wheel. It has been the common practice in the art in using buffing wheels of this type to provide two or more center portions or mounts of different diameters. A given set of fabric buffing members is first used on the smallest center mount. Thereafter, when the fabric has been worn a predetermined amount, reducing the working diameter of the assembly and consequently reducing its peripheral speed below a predetermined minimum, the fabric members have been removed from such small center mount and remounted upon a center mount of larger size. In this way, by remounting fabric members upon center mounts of progressively larger size, substantially full wearing capacity of the fabric parts can be obtained and waste thereof is reduced. However, it will be apparent that if the means for mounting the buffing members upon center mounts is not convenient and adapted for speedy manipulation and use, a large amount of time is consumed in the mounting, removal and remounting of the fabric members, and the saving effected by the avoidance of waste of the fabric members is at least partially offset by the cost of labor in the transfer of the buffing members from one center mount to another. Inasmuch as a plurality of fabric elements are secured to each center mount and it is common to use a plurality of such assemblies of center mounts and fabric elements upon a single shaft to form one buffer assembly, any small saving of time in the application and removal of an individual fabric buffing member will result in a substantial total saving of time for each buffer assembly.

Therefore, it is the primary object of this invention to provide a buffing wheel which is so constructed that it can be assembled and disassembled easily and quickly.

A further object is to provide a buffing wheel having a center mount and a plurality of fabric members effectively and detachably secured at the periphery of said mount by a novel attach-

2

ment means effecting a readily releasable hooked engagement of the attached parts.

A further object is to provide a buffing wheel comprising a center mount with hook elements and fabric members carrying hook-engaging parts wherein the center mount is constructed to so position fabric members as to retain said members against release without requiring the use of separate retainer means.

Other objects will be apparent from the following specification.

In the drawing:

Fig. 1 is a face view of one embodiment of the invention.

Fig. 2 is a sectional view taken on line 2—2 of Fig. 1.

Fig. 3 is a fragmentary face view of another embodiment of the invention.

Fig. 4 is a fragmentary detail sectional view taken on line 4—4 of Fig. 3.

Fig. 5 is a perspective view of a fabric buffing member.

Fig. 6 is an enlarged central sectional detail view of a fabric buffing member.

Referring to the drawing, and particularly to Figs. 1 and 2 thereof, the numeral 10 designates a center mount which constitutes a rigid metal plate. The plate 10 is preferably circular in shape and has a plurality of integral hook portions 12 projecting therefrom. The hook portions 12 are equally spaced apart about the periphery of the plate 10 and are inwardly return bent. Each of the hook portions 12 is spaced from the center of the plate 10 an equal distance. A circular retaining plate 14 is adapted to bear against the face of the plate 10 in a plane intersecting the hook portions 12. The plate 14 is of a diameter slightly less than the spacing of the inner edges of the hooks 12 from the center of the plate 10. Consequently, when the plate 14 is positioned as illustrated in Fig. 2, it serves as a retainer to prevent the release from the hook 12 of any member engaged therewith. The plates 10 and 14 have central openings 16 therein adapted to fit around a shaft (not shown). In the event it is desired to provide a wide buffing wheel, a plurality of plate units may be mounted upon the shaft in predetermined spaced relation with suitable spacers encircling the shaft and interposed between the adjacent plate units 10 and 14 in a manner well understood in the art.

A plurality of buffing members 18 are mounted upon the center mount of plate 10 by means of the hooks 12. Each of these buffing members 18 is preferably of the construction illustrated in

Figs. 5 and 6 and comprises a plurality of fabric pieces arranged side by side and preferably constituting concentric disks. One or more surfaces of the fabric disks are positioned reinforcing and rigidifying members 20 which members 20 are preferably of rectangular form and are positioned at the center of the fabric disks, being secured thereto by sewing or stitching 22 which serves also to hold the fabric disks together. A metal plate 24 bears against one surface of the buffering element assembly, preferably being of narrow elongated form and provided adjacent its opposite ends with apertures 26. An eye member is carried by each buffering member 18, the same preferably being formed of rigid wire or other material adapted to retain its shape when subjected to substantial force. The eye member preferably constitutes a central portion or run 28 spaced outwardly from and substantially parallel to one surface of the buffering member, as here shown being the surface opposite that at which the reinforcing members 20 and 24 are located. The wire member is bent to provide shoulder portions 30 at the opposite ends of the run 28 which extend toward the buffering member and from which project portions 32 which bear flat against the surface of the buffering member. Substantially perpendicular portions 34 are formed at the ends of the portions 32 and pass through the buffering member, the reinforcing members 20, and the apertures 26 of the metal plate 24. The free or terminal end portions 36 of the wire are then bent inwardly to bear against the inner surface of the plate 24. As here shown, the terminal portions preferably abut at their ends and may be welded, soldered or otherwise secured together at 38. It will be apparent, therefore, that each buffering member has a rigidified and strengthened central portion at which an eye is anchored and that the eye is so constructed that the portions 32 and 36 firmly clamp the same in place and serve to position the run 28 in predetermined spaced relation to one face of the buffering member.

A buffering member 18 of the character above described is secured to each of the hooks 12 upon a center mount 10 by insertion of the run 28 of the eye thereof into the hook 12. After the members have been so assembled, the retainer plate 14 is applied and the parts are then held against disassembly. Observe in this connection that the eye members, including the parts 28 to 36, inclusive, lie substantially in the plane of the center mount 10 and that the longitudinal dimension of each of the reinforcing parts 20 and 24 of each buffering member is parallel to the center mount 10. The buffering members are of such size that, when they are so assembled, they will engage each other adjacent to the ends of the reinforced longitudinal centers of the buffering members. Upon rotation the members 18 assume a form projecting outwardly as shown, due to centrifugal force. In this form the members 18 will be substantially flat to present a large surface area and will be folded at their margins so that the entire marginal part thereof will be confined as to peripheral extent and also as to the dimension thereof laterally of the center mount. The eye members have a snug but free fit in the hook portions 12 which facilitates their insertion in and removal from the hooks very rapidly and in a period of time much less than the time required by the attachment means heretofore employed. It will be observed that the trans-

verse dimension of the hooks 12 is such that a substantial area of contact is provided which insures a firm engagement of the eye with the hook to prevent rocking action of the buffering members in the direction of the length of the eye members during use of the buffering wheel. The reinforcing members 20 and 24 lie in planes transverse of the plane of the center mount 10 and serve effectively to anchor the eye members 28 to the buffering wheel, and in addition serve also, because of the tendency thereof to rigidify the center of the buffering members, to control the shape which such members assume under the action of centrifugal force in operation. In other words, said members provide a substantially flat central portion of the buffering members at all times, from the margins of which flat rigid center portions the free outer portions of the buffering cloth fold to assume the position shown in Figs. 1 and 2. It will be apparent, therefore, that when it is desired to assemble a buffering unit of the character shown in Fig. 1, and, subsequently, when it is desired to disassemble the same and to remount the partly worn members 18 upon a center of larger diameter, very little time is required to accomplish these purposes since the hooks permit free and quick application of the eyes thereto and removal of the eyes therefrom.

In the modified embodiment of the invention illustrated in Figs. 3 and 4, I have taken advantage of the rigid character of the center portion of each buffering member provided by the reinforcing members 20 and 24 thereof for the purpose of omitting the use of a retainer such as the plate 14 used in the Fig. 1 embodiment. This is accomplished by forming the center mount 50 from a plate of polygonal outline when fabricated as illustrated in Fig. 3. While Fig. 3 illustrates a plate of diagonal shape, it will be understood that the number of sides of the plate may be varied, depending upon the size of the buffering wheel desired and the size of the different members 18 employed therewith. To provide such a construction, the polygonal plate 50 is provided with a pair of slots 52 which are equally spaced from the end of the edge of the plate 50 adjacent thereto. The hooks 54 are formed between said slots 52 and the provision of the slots accommodates the arrangement best illustrated in Fig. 4, wherein in the outermost portion of the surface of each hook at 56 is tangent to the plane in which the adjacent edge portion 58 of the plate lies. In other words, the hooks 54 do not project beyond the edges 58 but rather lie substantially in the plane thereof.

The buffering members 18 used in this embodiment are of the same construction shown in Figs. 5 and 6 and described hereinabove. The runs 28 of the eyes of the different members are engaged and anchored at the hooks 54 in the same manner described above. In this instance, however, a firm solid abutment of substantial length and width is provided by the center mount for the central rigid portion of each buffering member as shown in Fig. 4. In other words, the flat substantially rigid center portion of each member 18 bears flat against the edge 58 and the hook surface 56. This prevents any tendency of the buffering member to rock about the run 28 as an axis after the buffering wheel has been assembled. In view of this positioning function and elimination of rocking about the run 28 of the eye of the buffering member, the buffering members will maintain their position at all times, whether stationary or in operation, so that it is not neces-

sary to provide a retainer closing the mouth of each hook 54 as is required in the construction illustrated in Fig. 1 where the buffing members are unrestrained except by the eye and may rock about the run of the eye as a center. In addition to the reduction in the number of parts involved, which in itself constitutes a substantial advantage especially in a buffing wheel formed of a plurality of center mounts arranged side by side upon a shaft, this device possesses advantages of light weight, lower cost, and minimum consumption of time to assemble and disassemble. The time saving is effected primarily by reason of the fact that retainer plates, such as plates 14, need not be handled and manipulated.

While the construction of the device as described herein is preferred, it will be understood that changes may be made in the construction within the scope of the appended claims without departing from the spirit of the invention.

I claim:

1. A buffing wheel comprising a metal plate having a central mounting aperture and a plurality of integral inwardly return-bent hooks spaced uniformly about the margin of the plate and equally spaced from said aperture, a plurality of fabric buffing members, a metal eye member carried by the center of each fabric member for reception by a plate hook, and a retainer plate bearing against said first plate with its margin adjacent the mouths of said hooks to prevent disengagement of said hook and eye.

2. A buffing wheel comprising a metal plate having a central mounting aperture and a plurality of integral inwardly return-bent hooks spaced uniformly about the margin of the plate and equally spaced from said aperture, a plurality of fabric buffing members, a metal eye member carried by the center of each fabric member for reception by a plate hook, and a retainer plate bearing against said first plate with its margin adjacent the mouths of said hooks to prevent disengagement of said hook and eye, said fabric buffing members being reinforced and stiffened at their center portions and said eye members being anchored at said reinforced center portions.

3. A buffing wheel comprising a metal plate having a central mounting aperture and a plurality of integral inwardly return-bent hooks spaced uniformly about the margin of the plate and equally spaced from said aperture, a plurality of fabric buffing members, a metal eye member carried by the center of each fabric member for reception by a plate hook, and a retainer plate bearing against said first plate with its margin adjacent the mouths of said hooks to prevent disengagement of said hook and eye, each eye member having a central portion spaced from one surface of the associated buffing member, end portions off-set from said central portion and bearing against said surface and return-bent terminal portions extending through said buffing member and cooperating with said end portions to clamp said buffing member therebetween.

4. A buffing wheel comprising a metal plate of polygonal shape having a central mounting aperture, a plurality of integral inwardly return bent

hooks formed at the margin of said plate, each hook being positioned substantially centrally of a flat edge portion of said plate with its outer curved surface substantially tangent to the plane 5 of said edge portion, a plurality of fabric buffing members, and an eye member secured to the center of each buffing member and detachably connected to a hook, said buffing members being bunched when assembled and the margins there- 10 of being outwardly projected by centrifugal force in use, the central portion of each buffing member bearing against and being positioned by the flat edge portions of said plate adjacent to the hook which mounts it.

15 5. The construction defined in claim 4, where- in each buffing member has a central rigidifying and reinforcing member at the portion thereof at which said eye member is secured, said last named member holding the portion of said buff- 20 ing member adjacent to said eye substantially flat in a plane perpendicular to said plate.

6. A buffing wheel comprising a rigid metal plate having a plurality of inwardly return bent hook portions formed integrally therewith at its 25 periphery in equi-spaced relation to each other and equally spaced from the center of the plate, said plate having aligned straight eye portions on opposite sides of each hook each lying in a plane tangent to the outer surface of the adja- 30 cent hook and perpendicular to said plate, a plurality of fabric buffing members each having a rigid substantially flat center portion bearing against the outer surface of said hook and against said adjacent edge portions, and an eye secured 35 to the center portion of each buffing member and detachably engaged by said hook and cooperating with the engagement of said center buffing part with said hook and edge portions to operatively position said buffing member on said plate.

40 7. A buffing member adapted for detachable hooked connection with a rigid center mount, comprising a plurality of superimposed sheets of flexible material secured together, an elongated reinforcing and rigidifying member secured to the central portion of said sheet assembly, and a rigid eye extending through said sheets and member and clamped thereto, said eye member having an elongated portion off-set from said 45 fabric and reinforcing parts and adapted for detachable connection with a hook on said center mount, the marginal portion of said buffing member being flexible.

55 8. A buffing member as defined in claim 7, wherein said reinforcing member constitutes a plurality of layers of a fabric of greater thickness and stiffness than said first fabric, and said eye is formed of rigid wire whose ends are positioned at the side of said buffing member opposite that adjacent to said off-set portion and are se- 60 cured together.

9. A buffing member as defined in claim 7, wherein said reinforcing member constitutes at least one layer of a stiff fabric and a metal plate of smaller size than said fabric and aperture 65 to receive runs of said eye passing therethrough and through said fabric.
